CLAIM

The ornamental design for a combination night light and bank, as shown and described.

DESCRIPTION

FIG. 1 is a front perspective view of a combination night light and bank showing our new design;
FIG. 2 is a top plan view thereof on a reduced scale;
FIG. 3 is a bottom plan view thereof on a reduced scale;
FIG. 4 is a side elevational view thereof on a reduced scale, the opposite side being a mirror image;
FIG. 5 is a rear elevational view thereof on a reduced scale; and,
FIG. 6 is a front elevational view thereof.

FIG 3

FIG 4

FIG 5
